(57) **CLAIM**

The ornamental design for a cutting blade support, as shown and described.

DESCRIPTION

FIG. 1 is a bottom perspective view of a cutting blade support showing our new design;

FIG. 2 is a bottom plan view thereof;

FIG. 3 is a top perspective view thereof; and,

FIG. 4 is a top plan view thereof.

The broken line showing of blade structures is included for the purpose of illustrating environmental structure only and forms no part of the claimed design.

1 Claim, 4 Drawing Sheets

FIG. 1

FIG. 2

FIG. 3

FIG. 4
